(57) **CLAIM**

The ornamental design for an earplug, as shown and described.

DESCRIPTION

FIG. 1 is a front plan view of an earplug showing our new design, the broken line showing is for illustrative purposes only and forms no part of the claimed design.

FIG. 2 is an elevational view thereof taken from the right of FIG. 1, the opposite side being a mirror image thereof;

FIG. 3 is an elevational view thereof taken from the top of FIG. 1, the opposite side being a mirror image thereof; and, FIG. 4 is rear plan view thereof.
